UNITED STATES PATENT OFFICE.

FRED C. HAMMOND, OF CHARLESTOWN, NEW HAMPSHIRE, ASSIGNOR OF ONE-HALF
TO WALTER W. SLACK, OF SPRINGFIELD, VERMONT.

TONE-AMPLIFYING APPARATUS FOR MUSICAL INSTRUMENTS.

Application filed July 8, 1922, Serial No. 573,669. Renewed February 27, 1924.

To all whom it may concern:

Be it known that I, FRED C. HAMMOND, a citizen of the United States, residing at Charlestown, in the county of Sullivan and State of New Hampshire, have invented new and useful Improvements in Tone-Amplifying Apparatus for Musical Instruments, of which the following is a specification.

This invention relates to means for amplifying the tone of a musical instrument having a resonant element, such as the body of a violin, violincello, viola, banjo, guitar, or mandolin, or the sound board of a harp or piano, the amplification being capable of being instantly changed by a leader or director, while the instrument is being played by a performer, to vary the volume of tone coming from the instrument.

An object of the invention is to provide a suitable device associated with the resonant element of the instrument, and connected with suitable electrical amplifying means, which is in turn connected with a receiver or loud speaker, whereby a director may vary the volume of tone of an instrument, or any number of instruments.

A further object of the invention is to provide a musical instrument which includes a sound post, such as that of a violin, etc., and a microphone associated with the sound post, and electrically connected with one or more stages of amplification, and in turn connected with a receiver or loud speaker.

Other objects will appear as the description proceeds.

Of the accompanying drawings forming a part of this specification,—

Figure 1 is a plan view of a violin showing the position of the microphone-carrying sound post.

Figure 2 is a longitudinal section of a violin, showing the microphone-carrying sound post in position between the front and back of the violin.

Figure 3 is a diagrammatic view, illustrating a suitable arrangement of the wiring of the circuits for the tone-amplifying device.

Figure 4 is a diagrammatic view illustrating a different arrangement.

Figure 5 is a diagrammatic view, illustrating another arrangement.

Like characters of reference are used throughout the following specification, to designate like parts.

In adapting my invention to a violin, or similar instrument, which includes a resonant body 1, and a sound post 2, I preferably provide the sound post with an enlarged central portion 3, which is hollowed out as at 4, to receive a microphone 5. It will be understood that the customary position for the sound post is immediately back of the bridge 6, and in a vertical position directly under the E string.

In the arrangement shown by Figure 3, the first circuit comprises a connection from the microphone, to dry cells 7, of which two or three may be employed, from thence to the primary of the coil 8, and from the opposite end of the coil 8 back to the other connection on the microphone. This circuit is called the primary circuit, and collects the tone vibrations when the instrument is played.

The secondary circuit commences with one side of the secondary of the coil 8, and connects with the grid 9 of an amplifier or audion bulb 10. The plate 11 of the bulb 10 connects with the positive side of the B battery, which is preferably approximately twenty-two volts. The negative side of the B battery connects to one post of a loud speaking receiver 12, and from thence to the post 13, and back to the opposite end of the secondary of the coil 8.

A third circuit connects the negative pole of a six-volt A or lighting battery with the pole 13, and from thence to one side of the filament 14. The other side of the filament connects with the arm 15 of the rheostat 16, and from thence back to the positive side of the A battery.

From the foregoing description, it will be seen that the sound waves from the instrument will be picked up by the microphone, and will be induced from the primary of the coil to the secondary of the coil. The amplifier bulb 10 will amplify the waves many times, until they are collected by the receiver 12, which also amplifies the volume.

It will be apparent that as many steps of amplification may be used as desired, so that an orchestra director may readily change the volume of music coming from the instruments equipped with this apparatus, to suit the requirements of the musical number being played.

The principle involved in this device is much similar to that of the wireless tele-

phone, wherein the loudness of the signals or music is only determinable by the number of steps of amplification employed.

It will further be understood that this 5 amplifying device may readily be installed in other musical instruments, so that when such installation is complete, an orchestra director will have the highest degree of control over his orchestra, and may modify the 10 tone of each instrument independently of the player.

In applying my invention to a musical instrument which does not include a sound post, and includes a resonant element, such 15 as the soundboard of a piano, the microphone may be secured in any suitable way to the resonant element, care being taken to prevent dampening of the vibrations.

It will be understood that many minor 20 changes in details and arrangement may be resorted to without departing from the spirit of the invention. For example, the arrangement shown diagrammatically by Figure 4 may be employed. This arrangement dispenses with the dry cells 7, and 25 switches off the current automatically when the filament is cut off.

The arrangement shown diagrammatically by Figure 5, materially reduces the 30 noises from a violin or similar instrument, caused by movements of the player's hand, and the scratching of the bow. This arrangement includes a three-point switch 20, adapted to cut out amplification to any 35 extent desired. In experimenting with apparatus, including the arrangement shown by Figure 5, I have attached the first tube plate to the third, with great improvement in the quality and volume of tone.

40 The invention may be adapted to wind

instruments of the brass family, such as cornets, French horns, trumpets, trombones and tubas, and to oboes, clarinets, English horns, bassoons, and saxaphones. In these 45 wind instruments I do not depend on the vibration of the body of the instrument, and depend instead on the vibrations of the air forced by the player from the bell of the instrument, the shape and material of the instrument giving the tone quality peculiar 50 to the instrument, whether it be of brass or wood. The vibrating air leaves the bell in cone form, and is applied directly to a microphone supported by any suitable means in the path of the vibrating air, the vibrations passing through the amplifying tubes 55 to any extent desired. The amplified tones blend with those of the instrument.

I claim:

1. A device of the character described 60 comprising a sound post for an instrument of the violin type, provided with an enlarged hollowed out central portion adapted to receive and house a microphone, in combination with means for amplifying the microphone current.

2. A sound post for an instrument of the violin type, provided with an enlarged hollowed out central portion, a microphone adapted to seat therein, and an electrical 70 amplifying circuit for said microphone.

3. A sound post for an instrument of the violin type, provided with an enlarged hollowed out central portion, a microphone adapted to seat therein, and an electrical 75 amplifying circuit including a loud speaking unit for said microphone.

In testimony whereof I have affixed my signature.

FRED C. HAMMOND.
